UNITED STATES PATENT OFFICE.

ELMER J. SPENCER, OF LUDLOW, KENTUCKY.

ECCENTRIC.

No. 825,428.

Specification of Letters Patent.

Patented July 10, 1906.

Application filed March 17, 1906. Serial No. 306,674.

To all whom it may concern:

Be it known that I, ELMER J. SPENCER, a citizen of the United States, residing at Ludlow, in the county of Kenton and State of Kentucky, have invented certain new and useful Improvements in Eccentrics, of which the following is a specification.

My invention relates to improvements in eccentrics and means for attaching the same to their shafts.

One of its objects is to provide an improved form of eccentric and means for conveniently and accurately adjusting the same relative to its shaft.

Another object is to provide such an eccentric with improved means for locking and holding it to its adjusted position.

It further consists in certain details of form, combination, and arrangement, all of which will be more fully set forth in the description of the accompanying drawings, in which—

Figure 1 is a side elevation, partly in section, of a device embodying my invention. Fig. 2 is a central vertical section on line $v v$ of Fig. 1. Fig. 3 is a view similar to Fig. 1, illustrating a modification. Fig. 4 is a central vertical section on line $x x$ of Fig. 3. Fig. 5 is a perspective view of the key or locking device. Fig. 6 is a diagram illustrating the arrangement of the eccentrics upon the shaft of a locomotive-driver.

My invention is applicable for attaching eccentrics or cams to their shafts for a variety of purposes, one of which is the attachment of the valve-controlling eccentrics of a locomotive to their shaft. As indicated in Fig. 6, the eccentrics $A A'$ of a locomotive are usually attached in pairs at opposite sides of the locomotive to the shaft b of the drivers B . The eccentric-straps are then connected by rods $a a'$ with the valves of the engine to control the admission and cut off of steam to the steam-cylinders. These eccentrics require to be carefully and accurately adjusted in order to bring the movements of the valves into harmony with the movements of the drivers, and once adjusted it is essential that they be firmly locked to their adjusted position and also against endwise movement on their shaft. It is also desirable that any one of said eccentrics may be unlocked from its shaft and readjusted without disturbing the other eccentrics.

In the accompanying drawings, Figs. 1

and 2, $C C'$ represent two sections of an eccentric-block which are mounted upon a shaft b , said sections having interlocking joints and being secured together by means of bolts D and nuts d , although the particular means employed for securing the sections of the eccentric together is not an essential feature of my invention. E represents a locking device or key having a base E' , which seats in a recess b' , formed in the face of the shaft, so that the outer face of the base E' preferably comes flush with and conforms to the outline of the shaft. The meeting edges or faces e and b^2 of the base E' and shaft b lock the key against movement in one direction relative to the shaft, while the meeting edges or faces $e' b^2$ prevent movement of the key longitudinally relative to the shaft. The base E' is locked in its recess in the shaft by the section C of the eccentric. The head E^2 of the key enters a recess c in the section C , so as to closely fit between the side walls c' thereof to prevent endwise movement of the eccentric on its shaft. Circumferentially recess c is slightly larger than head E^2 , so as to permit a limited adjustment of the eccentric relative to head E^2 sufficient to bring the movements of the valve controlled by the eccentric into harmony with the movements of the drivers. This adjustment is effected, preferably, by means of set-screws $H H'$ tapping into the section C and bearing against opposite sides of head E^2 . By manipulating screws $H H'$ the desired position of the eccentric may be quickly and accurately secured, after which the eccentric is firmly locked in place by means of set-screws I , which tap through the hub of section C and bear upon the base E' , forcing the same into close contact with the shaft and locking all the parts together. It will be noted that any injury caused by the points of set-screws I will occur to the face of base E' and can be remedied by replacing the key by a new one.

In the modification Figs. 3 and 4 the eccentric is locked to its shaft by means of tapered keys $K K'$, which seat in slots k in the hub of section C and are drawn into place and locked against displacement by means of nuts k' engaging the threaded ends of keys $K K'$. The inner faces of keys $K K'$ bear against the base E' , forcing the same into contact with the shaft. L represents the eccentric-strap encircling the eccentric and to which the valve-controlling rods

a or *a'* are attached. It will be noted that any one of the eccentrics may be unlocked from the shaft and readjusted or, if desired, removed from the shaft without disturbing 5 the remaining eccentrics.

The device herein shown and described is capable of considerable modification without departing from the principle of my invention.

10 Having described my invention, what I claim is—

15 1. In a mechanism of the character indicated, in combination with a shaft having a recess, a first or locking member fitting said recess and held in fixed relation to the shaft and provided with a projection, a second member or member to be locked to the shaft composed of two sections, means for uniting said sections together upon the shaft, the 20 hub portion of one of said sections being provided with a recess into which said projection from the locking member enters, adjusting-screws engaging opposite sides of said projection, and means other than said adjusting-screws for clamping said locking member in the recess of the shaft and said second member thereto.

25 2. In a mechanism of the character indicated, a shaft, having a recess, a locking member fitted into said recess and held thereby in fixed relation to the shaft and provided with a projection, an eccentric composed of two sections and means for uniting said sections together about the shaft, a recess being

provided in the hub portion of one of said sections, said projection from said locking member entering said recess and closely fitting the same in one dimension and loosely fitting said recess in the other dimension, and adjustable means for shifting said projection 40 in said recess to effect the desired adjustment of the eccentric relative to the shaft.

3. In a mechanism of the character indicated, a shaft having a recess, a locking member having a base fitted into said recess and held thereby in fixed relation to the shaft and provided with a projection, an eccentric composed of two sections and means for uniting said sections together about the shaft, a recess being provided in the hub portion of 45 one of said sections, said projection from said locking member entering said recess and closely fitting the same in one dimension and loosely fitting said recess in the other dimension, adjustable means for shifting said projection 50 in said recess to effect the desired adjustment of the eccentric relative to the shaft, and adjustable means reacting between the base of said locking member and the hub portion of said eccentric to force said 55 base into the recess in the shaft and to lock said eccentric to said locking member.

In testimony whereof I have affixed my signature in presence of two witnesses.

ELMER J. SPENCER.
